UNITED STATES PATENT OFFICE.

JOHN HENRY DARBY, OF BRYMBO, ENGLAND.

CENTRIFUGAL MACHINE.

SPECIFICATION forming part of Letters Patent No. 618,814, dated January 31, 1899.

Application filed October 20, 1898. Serial No. 694,102. (No model.)

To all whom it may concern:

Be it known that I, JOHN HENRY DARBY, a subject of the Queen of Great Britain, residing in Brymbo, near Wrexham, in the county 5 of Denbigh, Principality of Wales, England, have invented certain new and useful Improvements in Apparatus for Depriving Coal, Slack, and other Material of Surplus Moisture, of which the following is a specification.

10 This invention relates to apparatus for separating the surplus water adhering to small coal, slack, and the like. It is best described by aid of the accompanying drawing, showing a section of my apparatus.

15 In the drawing, A is the inlet-hopper for moist slack; B, a shaft passing through same; C, a worm on shaft B drawing the slack into the whizzer; D, a conical wrought-iron cone formed of one-quarter-inch plates suitably 20 stayed with three or more studs E, attached to a collar F on shaft B. On this collar, too, a wrought-iron disk G is fixed, projecting, as shown, to near the periphery of the cone D, but allowing sufficient space for the slack to 25 pass. H is a similar disk. In the drawing there are only two, but in some cases I may have three or four.

I is a further set of supporting-studs, J an angle-iron, and K another collar on the shaft 30 B. These two are connected by the studs L. L is a conical ring fitting against the cone D. Between ring L and cone D and the projecting ends of the studs I and the angle-iron J perforated sheets M are fixed. These perforated sheets are further supported at intervals by bars N.

O is an outside conical stationary cover, and P the end stationary cover; Q, the outlet for water, and R the outlet for dried slack. As 40 the outlet R is liable to be choked up, I place a shaft S, driven by pulley T, passing through this outlet, with beaters U U thereon. These continually revolving keep the outlet open.

The mode of action is as follows: The slack 45 or other material is fed into the inlet A and is passed by the worm C into the revolving cone D M. The slack immediately adjoining the perforated sheets M is sufficiently dried and rapidly passes away into the space W 50 and the exit R. The slack, however, farther away from the perforated sheets comes in con-

tact successively with the disks G H. The remaining slack is thrown by the revolving drum against the disks, and striking them approximately at right angles is disintegrated 55 or pulverized, and so rendered suitable for coking without further grinding the slack. It is further deflected back onto the casing, is then thrown against the next disk, and again deflected back onto the casing, and so on 60 until it reaches the extremity at angle-iron J. Angle-iron J, besides acting as a skeleton on which to fix the perforated sheets, also sheds off any water which would have a tendency to creep up the outside of the perforated sheets 65 and enter the space W. It throws the water off into the outlet Q. It will thus be seen that in exact proportion as the layers of slack are distant from the perforated plates they are impeded in their travel, and so for a longer 70 time are exposed to the centrifugal action, whereas the slack, which can easily get rid of its water, is exposed for a shorter time to the centrifugal action.

A machine made on this principle and from 75 which the drawing has been taken has been at work for some time at the Broughton Solvay coke ovens. It is run at approximately four hundred and thirty revolutions per minute and treats eight tons of slack an hour, 80 entering with about eighteen per cent. of water and leaving with about six per cent. to eight per cent.

Although I have described the actual apparatus, I do not bind myself to this exact arrangement, as it is obvious that the shaft B can be horizontal, inclined, or even vertical, as the slack will in any case creep up the sloping sides. In practice, however, a horizontal or slightly-inclined shaft appears the 90 most efficacious.

I declare that what I claim is—

1. In combination with a suitable casing provided with a feed-opening at one end; a shaft extending through said frame; a frusto-conical shell mounted upon said shaft, comprising an imperforate section located adjacent to the feed-opening, and a perforate section connected thereto and extending toward the discharge end of the casing; and disks 95 secured upon the shaft within the shell, substantially as and for the purpose described. 100

2. In a centrifugal separator, the combination of a suitable casing provided with a feed-opening at one end, and a discharge-opening at its opposite end; a shaft mounted in said casing and extending through said feed-opening; a worm carried by that portion of the shaft within said feed-opening; a frusto-conical shell mounted upon the shaft within the casing, comprising an imperforate section D, 5 and a perforate section M connected thereto and extending toward the discharge-opening; and disks G and H mounted upon the shaft.
3. In a centrifugal separator, the combination of a suitable casing provided with a feed-hopper A, a liquid-discharge opening Q, and 10 a discharge-exit R; a shaft extending through the casing and the hopper; a frusto-conical shell mounted upon the shaft within the casing, comprising an imperforate section D and 15 a perforate section M connected thereto and extending toward the exit R; disks G and H also secured upon the shaft within the shell; 20

and beaters located within the discharge-exit R.

4. In a centrifugal separator, the combination of a suitable casing provided with a feed-hopper A, a liquid-discharge opening Q and 25 an exit R; a shaft extending through the casing and the hopper; a worm carried by the shaft within the hopper; a frusto-conical shell mounted within the casing upon the shaft, comprising imperforate section D and 30 perforate section M; disks G and H secured upon the shaft within the shell; deflecting-rim J carried at the outer end of section M; 35 and beaters located within the discharge-exit R.

In witness whereof I have hereunto signed my name, this 11th day of October, 1898, in the presence of two subscribing witnesses. 40

JOHN HENRY DARBY.
